STEP OR RUNG

Filed Oct. 4, 1938

UNITED STATES PATENT OFFICE

2,179,412

STEP OR RUNG

Charles F. Keuthan, Middletown, Ohio

Application October 4, 1933, Serial No. 233,312

2 Claims. (Cl. 228—46)

My invention relates to improvements in steps and to a method of forming the same, particularly to the type of step or rung commonly used in manholes, pools and on stacks and the like.

5 Heretofore steps constructed for use in manholes and the like were of two distinct types, for instance those constructed of certain wrought or rolled metals and those from castings. Those constructed of wrought or rolled metals while having the desired strength were lacking in resistance to the deteriorating effect of certain corrosive and destructive elements ever present in manholes and the like. Those constructed from castings, while having the desired resistance to the corrosive and destructive elements in the manholes, were highly unsatisfactory for the reason that they were weak in transverse and shearing strength. Therefore, the use of either type of step has always presented a hazard to workmen using them for the reason that if they were not frequently replaced breakage would occur which often resulted in not only serious injury but often in death.

It is therefore one of the principal objects of 25 my invention to provide a step especially adaptable for use in manholes, sewers and the like so constructed as to resist the corrosive effects of the elements present in the manholes, and at the same time maximize the strength of said step.

30 An important object of my invention is to provide a step or rung of the character described which is simple in construction, durable in use, and economical in manufacture.

Another object of my invention is to provide a 35 simple and efficient method of forming steps or rungs of the above described character.

Other objects and advantages will be apparent from the following description, appended claims and annexed drawing.

40 Referring to the drawing wherein like reference characters designate like parts throughout the several views:

Figure 1 is a bottom plan view partly in section of my invention.

45 Figure 2 is a side elevation thereof.

Figure 3 is a detail sectional view taken on the line 3—3 of Figure 1.

Figure 4 is a horizontal sectional view partly in section of a modified form of my invention.

50 Figure 5 is a detail fragmentary side elevation of a modified form of tread.

Figure 6 is a sectional view taken on the line 6—6 of Figure 5.

55 My novel step or rung 5, in the preferred embodiment illustrated in Figures 1 to 3 inclusive,

is of a substantially U-shaped configuration in plan and fashioned with a horizontally disposed tread section 6 formed with right angular disposed spaced parallel extending supporting sections 7 which terminate at their outer ends in downwardly extending right angular disposed end sections 8 adapted for engagement with the face of a manhole or the like and coact with the latter to maintain the tread section 5 in a horizontally extending plane, it being understood that any desired number of the steps may be attached to the wall of the manhole, one above the other to provide means for descending and ascending to within and without said manhole.

The tread and supporting sections 6 and 7 respectively are of an integral construction and formed with inner and outer portions 9 and 10 respectively, the inner portion constituting a core member extending centrally through the outer section and fashioned with ends 11 projecting an appreciable distance beyond the ends of the sections 8 and in axial alignment with said sections for embedding within the wall of the manhole, and is also capable of being utilized during the manufacture of the invention in a manner to assist in the casting of the outer portion about said inner portion. The core member is of a solid construction formed of wrought or rolled metal while the outer portion 10 comprises a ferrous casting.

From the foregoing it will be apparent that by utilizing a wrought or rolled metal core covered by a ferrous casting, I provide means for resisting the deteriorating effects of the corrosive elements within manholes and at the same time 35 maximize the strength of the device, it being understood that the outer portion serves to protect the inner portion or core from the effects of the corrosive elements.

As illustrated in Figure 4 of the drawing a 40 modified form of my invention comprises a core member 15 in the form of a tube which, while lending desired strength to the outer portion or ferrous casting 16, serves to lighten the weight of the step or rung to facilitate transporting of 45 the same and to effect an economy in the manufacture thereof.

In the modified form illustrated in Figures 5 and 6 of the drawing, the tread section 20 is provided with a serrated outer face 21 to preclude 50 slipping therefrom by workmen when descending and ascending the manhole or the like.

The method of forming my improved step consists of fashioning a length of rolled or wrought metal to form a tread section provided at the 55

ends thereof with right angular disposed supporting sections and of casting about said length of wrought or rolled metal an outer portion of ferrous metal and of providing the ends of the latter with right angular disposed wall engaging sections.

What I claim is:

1. A step formed with inner and outer portions, said outer portion sheathing said inner portion and constructed of a corrosion resistant material constituting a protection for said inner portion against corrosive elements present in manholes and the like, said outer portion fashioned with angularly disposed end sections adapted to engage the wall of a manhole and coat with said wall to maintain said step in fixed condition relative to said wall.

2. A step formed with inner and outer portions, said outer portion sheathing said inner portion and constructed of a corrosion resistant material constituting a protection for said inner portion against corrosive elements present in manholes and the like, said inner portion having anchoring end sections adapted to extend within the wall of a manhole for anchoring said step to said wall, said outer portion fashioned with angularly disposed end sections relative to said anchoring end sections of said inner portion and adapted to engage the outer face of said wall and coat with the latter in maintaining said step in fixed condition relative to the wall.

CHARLES F. KEUTHAN.
